UNITED STATES PATENT OFFICE.

ALLEN H. MIX, OF BURLINGTON, VERMONT, ASSIGNOR TO PORTER SCREEN MANUFACTURING COMPANY, OF BURLINGTON, VERMONT.

METAL WINDOW-SCREEN.

No. 810,962.

Specification of Letters Patent.

Patented Jan. 30, 1906.

Application filed November 14, 1905. Serial No. 287,273.

To all whom it may concern:

Be it known that I, ALLEN H. MIX, of Burlington, in the county of Chittenden and State of Vermont, have invented a new and useful Improvement in Metal Window-Screens, of which the following is a specification.

My invention relates to that class of window-screens in which the frame is metallic and hollow.

The invention has more particularly to do with the construction of the bars of which the frame is composed, the object being to obtain a construction which shall be strong and stiff and yet simple to make and which at the same time shall permit of the ready rewiring of the screen in case of damage to the wire-cloth.

I shall proceed to describe in connection with the accompanying drawings, forming part of this specification, the screen construction in which my invention is embodied and will then point out in the claim that which I believe to be new and of my own invention.

In the drawings, Figure 1 is a face view of the screen, the center portion of it being broken way to reduce its dimensions. Fig. 2 is a cross-section of one of the frame-bars on line 2 2, Fig. 1, on enlarged scale. Fig. 3 is a view of a portion of one of the bars with filling-strip removed on enlarged scale. Fig. 4 is a like view of a portion of a filling-strip.

The screen is composed of the frame-bars A and the wire-cloth B, which is held in place by filling-strips C, that form, in effect, a part of the bars. The corners of the frame may be mitered and welded or soldered together, or the bars at these points may be secured together in any other suitable way, my present invention having to do only with the construction of the frame-bars. Each bar A is made of a strip of sheet metal which is bent into a box-like hollow structure of rectangular form in cross-section with parallel sides and top and bottom, the top, however, not being completely closed, but being formed by inturned portions a, extending toward each other in the same plane from opposite sides of the bar with an opening b between their opposed edges. Each filling-strip C is made from sheet metal bent so that it will have a channel-bar or U form in cross-section. It is of a width to fit and fill the opening b between the opposed edges of the limbs a of the bar A, and its free ends are bent

slightly inward toward each other, so as to facilitate the entrance of the filling-strip into the opening b.

The edge of the wire-cloth is laid over the opening b so as to partly bridge the latter, and then the filling-strip is pressed down into the opening, bending down in its course the wire-cloth, which is caught and held, as shown in Fig. 2, between the edge of one of the limbs a and the adjoining side of the filling-strip. The farther the strip is pushed down the tighter is the grip on the cloth, until by the time the filling-strip is forced home the head of the strip will be between the edges of the limbs a, which act as biting-jaws to grasp and hold the parts most firmly in position. At the same time it will be noted that by means of a proper tool the filling-strip can be easily lifted out and removed from the frame-bar whenever it is desired to remove the wire-cloth.

The form of the frame-bar A itself, with inturned limbs a lying in the same plane, imparts to the bar great stiffness and strength, and as the filling-strip is grasped only by the opposed biting edges of these limbs the arrangement is such that the thrust of the filling-strip on these limbs a is effectively resisted.

I am aware that it is not new to use a longitudinal filling-strip applied to and fitting in the recessed face of a screen-rail or frame-bar for the purpose of holding the wire-cloth, and this I do not claim.

What I do claim herein as new and of my own invention is—

In a metal window-screen, a hollow box-like sheet-metal frame-bar with parallel sides and top and bottom, the top formed by inturned limbs a extending toward each other in the same plane from opposite sides of the bar, with a longitudinal opening b between their opposed edges, in combination with a sheet-metal filling-strip, of substantially channel-bar or U cross-section to fit and fill said opening, and wire-cloth gripped between one side of the filling-strip and the opposed biting edge of the adjoining limb a of the bar, as and for the purposes hereinbefore set forth.

In testimony whereof I affix my signature in presence of two witnesses.

ALLEN H. MIX.
